Inventor

HARRY FRISCHER

By his Attorney
Alfred N. Mervin

Patented July 21, 1925.

UNITED STATES PATENT OFFICE.

HARRY FRISCHER, OF NEW YORK, N. Y.

PROCESS OF EMBOSsing PLAITING.

Application filed April 10, 1923. Serial No. 631,187.

To all whom it may concern:

Be it known that I, HARRY FRISCHER, residing at New York, in the county and State of New York, have invented certain new and 5 useful Improvements in a Process of Embossing Plaiting, of which the following is a specification.

This invention relates to a new and improved method of embossing plaited material and one of the objects of the invention 10 is to provide a method such that embossed or raised designs may be produced in plaited material without injury to the plaits and whereby the embossing is relatively higher 15 or deeper than it has been possible to produce embossing in methods hitherto practiced.

Other objects and aims of the invention more or less specific than those referred to 20 above, will be in part obvious and in part pointed out in the course of the following description of the steps and the relation of each step to one or more of the others thereof employed in carrying out my method, and 25 the scope of protection contemplated will be indicated in the appended claims.

In the accompanying drawing wherein I 30 have illustrated a preferred form of embodiment of my invention:

Figure 1 is a plan view showing one way 35 in which my improved method may be carried out; and

Figure 2 is a sectional view taken on the line 2—2 of Figure 1.

Referring now to the drawing wherein 40 similar reference characters refer to similar parts throughout both views thereof, the reference numeral 1 denotes a strip of textile material which has been plaited as shown.

In the present embodiment of the invention I have shown the material plaited with what is known as a "box plait", although it will be understood that other kinds of plaiting known as accordian plaiting, may be operated upon according to my improved method.

In carrying out my method I provide a pair of opposed rollers suitably driven at 50 equal speeds in opposite directions. These rollers are indicated at 2 and 3 respectively. The rollers are heated by any suitable method. Roller 1 has cut or otherwise formed therein the particular design that it 55 is desired to emboss upon the plaited material.

Reference numeral 4 denotes a strip of relatively soft material, such for instance as, flannel, said strip having a width substantially as that of the plaited material to be 60 embossed.

In carrying out my improved method the plaited material is superimposed upon the strip of flannel 4 and the two strips are then passed between the rollers as clearly shown 65 in Figure 2. It will be noted that the strip of flannel 4 runs in contact with roller 3. During the passage of the two strips between the rollers the relatively soft flannel causes the plaited material to be forced upwardly 70 into the depression 5 of the roller 2, thereby causing the plaited material to take on the form of the design of the roller 2, whereby the plaited material is embossed as indicated in Figure 1. The heat applied to the plaited material by the rollers between which it passes causes the embossing to permanently 75 retain its shape.

It will accordingly be seen that I have provided a method well adapted among 80 others, to attain all of the objects above stated, in an exceedingly simple and efficient manner.

As many changes could be made in this construction without departing from the 85 scope of the following claims, it is intended that all matter contained in the above description or shown in the accompanying drawing shall be interpreted as illustrative only and not in a limiting sense.

Having thus described my invention what I claim as new and desire to secure by Letters Patent is:

1. The herein described method of embossing plaited textile material, which consists in providing a pair of mating rollers, one of which has formed therein the design to be embossed, providing a strip of soft textile material, such as flannel, laying said strip of flannel and the material to be embossed in superimposed relation, and then passing them between said rollers.

2. The herein described method of embossing plaited material, which consists in providing a pair of mating rollers, one of which rollers is plain and the other has formed therein the design to be embossed, providing a strip of relatively soft textile material, such as flannel, laying said strip of flannel and said material to be imposed in superimposed relation, and then passing said assembly between said rollers with the

flannel side thereof engaged with the embossing roller.

3. The herein described method of embossing plaited textile material, which consists in providing a pair of mating rollers, one of which is plain, and the other having formed therein the design to be embossed, heating said rollers, providing a strip of relatively soft textile material, such as flan-

nel, providing a strip of plaited textile material, laying said strip of flannel and the strip of plaited material in superimposed relation, and then passing them between said rollers with the flannel side of the assembly engaged with the embossing roller. 10

In testimony whereof, I affix my signature. 15

HARRY FRISCHER.
